FUSEE FLARE

Philip E. Damon, Ames, Iowa

Application July 26, 1937, Serial No. 155,752

7 Claims. (Cl. 67—55)

My invention relates to flares of the kind which are used as signals on highways, and as a cheap portable light.

It is my general object to provide a cheap, reliable flare which can be ignited in a few seconds and which will burn for a relatively long period of time and which can be used for protection at night by trucks and vehicle drivers as an emergency signal. I thus attain the quick positive starting action of the fusee together with the long burning qualities of the flare.

In this connection, it is one of my purposes to overcome many objectionable and disagreeable features of flares now in use.

15 A particular object is to provide a cap which will protect the wick and inflammable material and can be adjusted to position to serve as a protector against wind or rain.

One of my particular objects is to provide a flare that will ignite in a few seconds in an extremely cold temperature.

Another object is to provide a flare with a wick and with simple means for sealing the wick so that it can be readily ignited and will burn steadily in a strong wind or rain.

An additional purpose is to provide a flare of such simple and inexpensive construction that after one use it can be thrown away. In this connection it is my purpose to provide such a 30 cheap and simple flare which, however, will prevent the escape of fuel oil or fumes.

With these and other objects in view, my invention consists in the construction, arrangement and combination of the various parts of my signal system, whereby the objects contemplated are attained, as hereinafter more fully set forth, pointed out in my claims and illustrated in the accompanying drawing, in which:

Figure 1 is an elevation of a wick sealed flare embodying my invention.

40 Figure 2 is a similar view enlarged, the metal cap being shown in vertical section.

Figure 3 is another elevation showing the metal cap removed and held in shielding position.

45 Figure 4 is a vertical sectional view of the top part of the flare, the inflammable or meltible cap for the wick and the ignitable material on such cap.

Figure 5 is a top or plan view of the top of the 50 restricted neck of the flare body; and

Figure 6 is a side elevation of my flare with a modified form of flame shield.

The flare of my invention consists primarily of a suitable container filled with kerosene or other fuel oil having a wick projecting upwardly above

the container. I have shown at 10 the container in the form of a cylindrical can with a top 11 which is convex and terminates in an upwardly extended restricted neck 12.

The upper end of the neck 12 is closed by the disc-like member 13, best shown in Figures 4 and 5. The wick 14 extends from the fuel holding part of the reservoir or container 10 upwardly through the hole 15 at the center of the top member 13 and projects upwardly as shown. Generally it is held in place by friction, although it can be fastened by some adhesive not soluble in the fuel oil.

It is important that provision be made to permit equalizing of pressure inside and outside the container when the wick is lighted. This, of course, can be accomplished by almost any arrangement which will permit air passage alongside the wick between the wick and the container or through holes or slots adjacent to or around the wick opening. If some such equalization is not provided, the air in the container will expand, by reason of the heat generated by the burning flame, and will be forced upward through the wick, causing liquid fuel to be thrown out into the air and over the container. Holes of any kind or shape may be used. I have shown here the member 13 provided with a series of holes 16 spaced outwardly from the hole 15. Outside the row of holes 16 the member 13 is provided with an annular channel 17 in its upper surface.

It is obvious that while the holes 16 permit the equalization of pressure, which is desirable, they also afford means for the kerosene or other oil to escape from the reservoir. If oil may so escape before the flare is used, it may easily run back into the reservoir.

One of the disagreeable features of flares now in common use is that they leak kerosene or other fuel and allow the escape of fumes and other fuel. The fumes are a source of danger and annoyance to the driver of the vehicle and possibly to passengers and sometimes they also have a very bad effect upon the goods being hauled. The escape of kerosene fumes into a cargo of butter, for instance, is almost a tragedy to the driver.

It has been almost impossible in the past to avoid this escape of fumes from the fuel oil and the difficulty is, of course, increased in flares that are used more than once.

To effect a satisfactory seal to keep the fuel from leaking out of the container or the wick, I provide a cover for that portion of the wick which projects upwardly from the container. The cover is indicated at 18 and is in the form of a down-

wardly opening cap, the edge of which is received in the channel 17. This cap is preferably made of an inflammable material or one which is fusible so that it is destroyed as a cover and to afford free access of air to the wick when the flare is lighted.

Preferably I employ a cover 18 of Celluloid or other similar material. It must not be impregnable to the liquid fuel and the fumes thereof and must be stiff enough to protect the wick. Celluloid and similar products have another advantage. They are soluble in acetone and I preferably use a little acetone in which some Celluloid has been dissolved as an adhesive to seal the cover to the container, the adhesive being indicated at 19 in Figure 4.

In the arrangement here shown, the holes 16 afford means for equalizing the pressure inside and outside the reservoir 10 when the flare is being burned. Thus the holes afford means for allowing air to enter the reservoir to take the place of fuel supplied to the wick.

The construction is such that if there should be any surplus fuel around the wick at any time before the flare is burned, such surplus can readily flow back into the reservoir, when flare is in vertical position for lighting.

The groove 17 helps in properly positioning the cover 18 and affords a channel to receive the sealing means.

It is important to be able to light the flare quickly and easily so that it will almost instantly function as a flare. For accomplishing this objective, I give the cover 18 an outside coating 35 either of friction ignitable material or of a little slower burning material, this coating being indicated at 20. If the coating 20 is of friction ignitable material, it can be ignited by friction in the ordinary way.

If it is of slower burning material, a small amount of friction ignitable material, indicated at 21, can be put on top of the material 20, as illustrated particularly in Figure 4. For a relatively slow burning material or coating the following formula will suffice with the parts mixed in substantially the proportions given:

	Grams
Potassium nitrate	68
Sulphur	27
Manganese dioxide	6
Potassium dichromate	9
Lamp black	2
Oxide of iron	5
Yellow dextrine	2
Celluloid	1½
Acetone—enough to make the mix like molasses	

For a friction ignitable coating the following formula with the parts in substantially the proportions given may be used:

	Grams
Chlorate of potash	34
Sulphur	2
Manganese dioxide	4
Potassium dichromate	5
Oxide of iron	7
Celluloid	2
Acetone—enough to make a mix like molasses	

If desired, a piece of adhesive 22 carrying a strip of striking material 23 may be provided for coating with the ignitable material on the cap.

I provide a metal cap 24 adapted to slip over and frictionally engage the neck 12 as shown in Figure 2 for example. At the lower edge, the cap 24 has a flared bell-like flange 25, the lower

edge of which may rest on the top 11 when the cap 24 is installed.

The cap 24 is connected to an annealed piece of wire or the like 26 which in turn is fastened to the top 11 or some part of the reservoir 10. The wire 26 is of any suitable material by which the cap may be held fastened to the flare body and stiff enough to hold the cap 24 in any position to which it may be adjusted. Thus, in Figure 2, the cap 24 is shown installed in position for protecting the cover 18 during shipment and storage and ordinary transportage of a flare.

In Figure 3 I have shown the parts in their positions when the flare is placed on the highway to serve as a signal, the cap 24 having been lifted off the flare to a position where it serves as a wind break and shelter and the flare having been lighted. On account of the nature of the member 26, the cap 24 can be adjusted to a variety of positions. For instance, in Figure 3, it is shown in full lines in position to serve as protection against the wind and in dotted lines in another possible position. The strength of the wind determines the correct position for the cap 24.

From the foregoing, it will be seen that I have provided a flare by which the objects originally set forth are attained. The holes 16 afford pressure equalizing means. The cover 18 affords a means to prevent the escape of fumes or fuel oil yet is easily inflammable or meltable so that a quick burning flare can be had. The flare can be quickly and easily lighted. The use of the cover 18 made of celluloid or low temperature fusible material, affords what is practically an instantaneously operating flare. The cap 24 protects the parts which might otherwise be injured during transportation and handling. This cap also functions to provide protection against wind or rain. It is adjustable to any position permitted by the wire 26 and it is obvious that this wire may be of such length as will afford almost any desired adjustment of the metal cap. I have found that by adjusting the cap to position with the large open end close to the wick and the smaller closed end toward the wind, the cap then affords very satisfactory protection to the burning flame. It will protect against a driving rain or snow. In a light rain or snow where there is little wind, the cap can be set to a position more directly above the wick. I have found by tests that this cap serves as an effective guard at an angle of almost 180 degrees. That is to say, if set directly into the wind, it will still function to protect against the wind even though the wind should shift almost 90 degrees in either direction. The flame is good enough so that it can be seen from every side, even from the side in which the cap 24 is located.

In nearly all cases where metal protective caps are used, they accumulate soot and carbon, especially in periods when there is a light wind or no wind. With an arrangement of the kind herein shown, there is very little accumulation of soot on the metal cap because the flame is not surrounded by it but always has one side open. Also because the cap is on the windward side of the flame, the flame is so protected and tends to spread behind the cap. This is illustrated in Figures 3 and 6. The flame is readily seen from the windward side of the cap. In a strong wind it is forced down around the neck 12 and helps vaporize the kerosene or other fuel.

Without the protection of cap 24 the wick itself would have to act as the wind protector. You would then have your flame (a small one)

only on the leeward side of the wick and none on the windward side. With a strong wind striking and cooling the wick, there would not be enough kerosene vaporized to supply the flame 5 and your flare would be extinguished.

The action of my cap 24 is entirely different (and I think better) than in the ordinary protector with holes. The holes in the ordinary protector permit cold air to strike the wick which 10 may extinguish the flare—proof of this lies in the fact that to extinguish them you simply blow through one of the holes. You can't do this with my flare because cap 24 has no holes.

The cap 24 so functions that the wick is in the 15 center of the flame and no cold wind reaches the wick.

In Figure 6 I have shown a modified form of the device. In this form the device is intended 20 to be like that already described with the exception that instead of the cap 24, I provide a shield member 30 in the form of a sheet or plate which is fastened to the flare body by a bendable member 31 which may be similar to the wire 26. The sheet 30 can be adjusted to a variety of protective 25 positions by adjustment of the bendable member 31.

It is my purpose in writing my claims to make them cover any modifications or changes in construction or arrangement of parts or use of materials which may be within the scope of my invention and such claims.

I claim:

1. In a flare structure, a hollow body for containing fuel, a wick in the top of the body, a 35 non-inflammable cap adapted to cover and protect the wick and rest on the body, and a stiffly bendable element secured to the body and to the cap and adapted to be bent to position for holding the cap in position to cooperate with 40 the body for wholly covering the wick, or holding the cap in positions to permit the wick to be ignited and to then shield the wick from wind or driving rain.

2. In a flare structure, a hollow body with a 45 reduced upwardly extending wick holding neck, a wick projecting through the neck, a non-inflammable cap having a portion adapted to frictionally fit over the neck whereby the cap will enclose the projecting portion of the wick for storage and transportation, and a stiffly bendable member connecting cap and the body to prevent 50 accidental loss of the cap, said member being capable of being adjusted to hold the cap in

position to shield the wick from the wind and yet permit the wick to burn, and to be bent to position where the cap is in its first-named position.

3. In a flare structure, a hollow body with a 5 reduced upwardly extending wick holding neck, a wick projecting through the neck, a non-inflammable cap having a portion adapted to frictionally fit over the neck and having a bell-shaped portion projecting from said last-described portion, whereby the cap will enclose the projecting portion of the wick for storage and transportation and a member connecting the cap and the body to prevent accidental loss of the cap, said member being capable of being bent 10 without breaking to hold the cap in position to shield the wick from wind and yet permit the wick to burn, and to be bent to position where the cap is in its first-named position.

4. In a flare structure, a hollow body for containing fuel, a wick in the top of the body, a shield and a stiffly bendable element secured to the body and to the shield whereby the shield can be repeatedly adjusted to positions at different angles and heights and at different points 25 circumferentially around the wick.

5. In a flare, a hollow body, a wick projecting through the top thereof, a hollow cap of fusible material, not impregnable by fuel oil or fuel oil fumes, overlying and covering the projecting 30 wick end, and friction ignitable material on the flare, adapted when ignited to fuse the cap.

6. In a flare, a hollow body, a wick projecting through the top thereof, a hollow cap of material 35 adapted to be destroyed by heat, not impregnable by fuel oil or fuel oil fumes, overlying and covering the projecting wick end, with its edge sealed to the body spaced from the wick, said body having vents between the edge of the cap and the wick.

7. In a flare, a hollow body having a closed top portion, a wick projecting through the top portion, a hollow inflammable cap surrounding the wick having an edge thereof secured to said top portion forming a sealed space around the wick, 45 said top portion having a venting passage initially communicating between the interior of the body and said sealed space and adapted to provide communication between the interior of the body and the atmosphere when the seal formed 50 by the cap is destroyed.

PHILIP E. DAMON.
